MEANS FOR AVOIDING THE DELETERIOUS
EFFECT OF DETONATION IN INTERNAL
COMBUSTION ENGINESOswald C. Brewster, Kansas City, Mo., assignor
to Brewster Development Corporation, New
York, N. Y., a corporation of Delaware

Application September 21, 1931, Serial No. 563,972

3 Claims. (Cl. 123—191)

My invention relates to a means and method for avoiding the deleterious effect of detonation of fuel in internal combustion engines. This detonation is commonly known as "knocking".

- 5 It has been found by a photographic study of the flame travel in the combustion space of an internal combustion engine using gasoline as a fuel, that the flame travels progressively from the ignition point at the spark plug at a substantially uniform rate. The speed of flame propagation is generally in the neighborhood of 70 feet per second. As the flame advances through the unburned portion of the fuel, the products of combustion produce a pressure which increases 10 rapidly. This increased pressure is formed more or less rapidly depending upon the characteristics of the fuel. The pressure increases until a point where the remaining charge of unburned gas which is situated in a zone farthest from the point 15 of ignition will burst into flame simultaneously throughout its entire volume. This is analogous to an explosion or detonation. The products of combustion released by this sudden burning or detonation of fuel produce a high pressure which 20 manifests itself in what is known as "knocking". The cause of this phenomenon is that the increased pressure produces a high temperature and this, aided by the radiation of heat from the burning fuel raises the entire mass of the unburned fuel beyond its kindling temperature, resulting in the ignition of the entire mass. This 25 self ignition of the fuel is analogous to the principle employed in the Diesel engine.
- If the initial compression is low so that substantially all of the fuel is burned before this condition is reached, no detonation will result. The point of detonation for a given cylinder and a given compression ratio will vary according to the different chemical characteristics of the different fuels inasmuch as varying minimum temperatures at which self ignition occurs will be 30 present in the different fuels. Gasoline containing a deterring agent, such as tetraethyl lead, iron carbonyl, or other so-called knock inhibitors, acts to slow down the rate of combustion and it is believed raises the effective temperature at which detonation occurs. Benzol, gasoline produced from certain selected crude oils, and gasolines produced by cracking under certain favorable conditions, have a naturally higher effective detonation temperature so that these fuels are said to have "anti-knocking qualities". The ordinary gasoline from paraffin base crudes, on the other hand, form a large percentage of our 35 gasoline production. This gasoline, having a lower effective detonation point, has a tendency to knock, especially where the motor is running under heavy load conditions or with a high compression ratio. Inasmuch as the efficiency of a gasoline engine increases with the initial compression ratio, it has been the practice to design internal combustion engines with high compression heads with the result that ordinary fuels will produce a severe knocking. When running at high speeds, the lower manifold pressure will 40 result in a lower compression ratio. It is for this reason that knocking is usually absent at higher speeds, though with the same fuel and the same cylinder head it will be present at lower speeds. This condition led to the proposal of providing means to automatically lower the compression ratio at low speeds. One example of a means for accomplishing this object is shown by Kondo in United States Letters Patent 1,719,705. It is observed that this patent provides an expansion 45 chamber connected to the cylinder head by a small orifice so that at low speeds the high compression will be relieved through the orifice and into the expansion chamber, while at high speeds there will not be sufficient time for the compression to escape into the expansion chamber.
- Another method has been proposed by Bullington in United States Letters Patent 1,782,395. Bullington suggests the formation of the compression space for the cylinder head in which a plurality of separated, interconnecting pockets are formed and the compressed fuel is directed into these separated pockets. The spark plug is located at a point intermediate these separated pockets and connected therewith by a plurality of 50 ducts. Upon sparking, ignition is supposed to take place in the various pockets simultaneously and this diffusion of the compression wave is supposed to prevent detonation.
- One object of my invention is to permit the use of ordinary gasoline in a high compression engine without the occurrence of destructive knocking.
- Another object of my invention is to provide means for absorbing the knock and depriving it of its harmful nature by preventing the sudden pressure produced by the knock from acting upon the piston, the wrist pins, the connecting rod and the crank bearings.
- A further object of my invention is to provide 55 means for wire-drawing the high pressure produced by the detonated fuel so that it may be used to perform work smoothly, thus avoiding the deleterious effect of the knock.
- The figure shows a section of a cylinder head.

equipped with one mode of carrying out my invention.

In general, my invention consists in not trying to avoid the knock as is done by Kondo or 5 Bullington, but rather to provide means in which the detonation may take place harmlessly and subsequently allowing the pressure generated by the detonated fuel to perform its work in a smooth and rhythmical manner.

10 More particularly, referring now to the drawing, the cylinder 1 and the piston 2 are of conventional design. The cylinder head 3 is secured to the cylinder in the usual manner to form the combustion space 4. A spark plug 8 is located as is 15 common practice over the fuel valve 5. At a point remote from the ignition point, as for example at the opposite side of the combustion space, a gasoline combustion chamber 6 is joined to the main combustion space 4 by an opening 7 20 which is more or less restricted, depending upon the compression ratio and the distance it is located from the ignition point. The size of the chamber 6 will vary, depending upon the compression ratio desired. For a high compression ratio, 25 the chamber 6 may be of a constant size and a smaller clearance provided between the top of the piston 4 and the cylinder head. The chamber 6 may be varied within certain limits to vary the compression ratio. It must, however, be of a sufficient size to perform its function. This function 30 will be hereinafter more fully described. The total volume of the combustion space 4 and the chamber 6 is used as the clearance volume in computing the compression ratio of the engine.

35 When the piston 2 is forced upwardly, it compresses the fuel and air mixture into the combustion space and the chamber 6, it being understood that the opening 7 leading to the chamber 6 is of sufficient size so that during the compression 40 stroke the pressure in chamber 6 is substantially the same or only slightly less than that in the main combustion space 4, that is that the pressure drop of the gas mixture in being forced through opening 7 is small. The ignition system 45 is timed as in the ordinary engine, to produce a spark at the spark plug 8 at some predetermined point of the compression stroke, usually from 15° to 30° of the angular crank travel head of the top dead center. The flame starts to travel progressively through the fuel mixture in all directions away from the spark plug in concentric, 50 increasingly larger circles. There is usually an interval of slow travel at the start due to the comparatively lower pressure. The speed of flame travel increases as the pressure. As the pressure increases, the speed of travel increases. The highest speed is usually reached by the time the 55 piston has arrived at the top of its stroke. The heat generated by the combustion, as well as the fact that the products of combustion occupy a greater volume than the original mixture, results in a rapid rise in the pressure existing in the combustion space. This results in the flow of gases into the chamber 6 again with a relatively small 60 pressure drop. It now becomes apparent why I have placed the chamber 6 as far as possible from the spark plug. It is obvious that the gases in chamber 6 will consist chiefly of the unburned fuel mixture. The pressure and temperature having 65 been increased due to partial combustion of the mixture, will produce the temperature of self ignition. The detonation always results from the explosive burning of the remainder of unburned mixture. This unburned mixture has been substantially isolated in chamber 6. If detonation 70

does take place, it will do so within chamber 6. The volume of chamber 6, it is to be understood, is so proportioned with respect to the entire combustion space that, up to the point when all of the fuel in the main combustion space 4 has been burned, the pressure and temperature of the unburned fuel mixture has not been raised to the self ignition point so that no detonation will occur. When, however, due to the increase of pressure and temperature, the self ignition point or 10 detonation point is reached, it will occur as has been seen, in chamber 6.

This detonation results in a very high pressure occurring almost instantaneously. Due to the 15 restricted opening 7, this high pressure is not transmitted to the working chamber 4 and is thus deprived of its destructive effect upon the piston, the wrist pin, the crank bearings, the connecting rod and the valves. The noisy effect which is 20 noticed and from which "knocking" derives its name, is obviated. It is to be noted that the duct 7 is so designed that, while it is large enough to produce only a small pressure drop at the compression pressure, yet it will be small enough to produce a substantially wire-drawn effect for 25 the high pressure produced by detonation. The pressure of detonation being wire-drawn through opening 7 allows this pressure to enter the working chamber 4 and to contribute its effect on the piston to do work. Thus it is seen that, during 30 the compression period and the early combustion stage, the velocity of the gases flowing through opening 7 and into chamber 6 is relatively low so that a low pressure drop takes place.

35 On the other hand, when the detonation occurs, the velocity is increased in the opposite direction, thus giving the very high pressure drop with its resulting wire-drawing effect during this 40 stage. The pressure drop, of course, varies with the velocity.

45 It is to be understood that, while I have shown one mode of carrying out my method, that various changes may be made in the details within the scope of the claims appearing below without departing from the spirit of my invention. It is, therefore, to be understood that my invention is not to be limited to the specific details shown and described.

Having thus described my invention, what I 50 claim is:

1. In an internal combustion engine, a cylinder head adapted to form a compression space with the piston, ignition means located in said compression space, a chamber communicating with said compression space through an orifice of reduced diameter, adapted to receive a portion of the fuel, said chamber being positioned at a point substantially most remote from the ignition means whereby the fuel contained therein will be ignited subsequent to the burning of the fuel in said compression space, whereby detonation will be substantially segregated in said chamber, and the shock of detonation on said piston will be reduced by said orifice.

2. In a device of the kind described, a main combustion chamber having an ignition point in which the combustion of gases takes place by relatively slow flame propagation, an auxiliary chamber in which the combustion of gases takes place by detonation due to increased pressure, said auxiliary chamber having an aperture in the path of travel of flame propagation in the main combustion chamber and of a sufficiently restricted area to permit the escape of gases from the auxiliary chamber accompanied by a reduction 75

of pressure, said aperture being positioned at a point substantially most remote from the ignition point.

3. In a device of the kind described, a main combustion chamber, an auxiliary chamber having an opening into the main chamber in the path

of travel of the flame front and restricted in area to the extent of permitting differences in pressure between the main chamber and the auxiliary chamber, said opening being positioned at a point substantially most remote from the ignition point. 5
